J. L. PERKINS

WORM THREAD POLISHING MACHINE

Filed March 31, 1927

FIG. I.

FIG. 8.

BY Julian L. Perkins,
Frank A. Cutler,
ATTORNEY

ATTORNEY.

UNITED STATES PATENT OFFICE.

JULIAN L. PERKINS, OF WEST SPRINGFIELD, MASSACHUSETTS, ASSIGNOR TO PERKINS MACHINE AND GEAR COMPANY, OF SPRINGFIELD, MASSACHUSETTS, A CORPORATION OF MASSACHUSETTS.

WORM-THREAD-POLISHING MACHINE.

Application filed March 31, 1927. Serial No. 179,954.

My invention relates to improvements in machines for polishing the threads of worms, and consists essentially of a hollow, rotary head open at one end, and provided inside with a liner having interior, circular teeth which are shaped to fit the worm threads to be polished, said teeth being without any lead, and a work-holding spindle arranged to rotate and for endwise movement in an adjustable and rocking or swinging bearing, and means to apply pressure to the spindle-carrying parts and thereby force the worm attached to said spindle into close contact with said liner, it being understood that said spindle is adapted to be moved to position said worm inside of the liner, together with such other parts and members as may be necessary or desirable in order to render the machine complete and serviceable in every respect, all as hereinafter set forth.

The primary object of my invention is to produce a comparatively simple and inexpensive, yet highly efficient, machine for polishing the threads of worms of different sizes, leads, and hands. By the latter term is meant the directions of threads on worms, the direction of the threads on right-hand worms being to the right, and the direction of the threads on left-hand worms being to the left.

A further object is to provide, in a machine of this character, convenient means or mechanisms respectively for rotating the work by hand, while said work is in contact with the polishing element, and thus made for varying at will both the amount of rotation imparted to the work while in contact with the polishing element, and the degree of pressure between said work and said element, whereby it is possible to polish the work to the best advantage and obtain the desired results.

Other objects and advantages will appear in the course of the following description.

I attain the objects and secure the advantages of my invention by the means illustrated in the accompanying drawings, in which—

Figure 1 is a top plan of a worm-thread polishing machine which embodies a practical form of my invention; Fig. 2, a right-

hand end elevation of said machine, the outer terminal of the work spindle being broken off, and a portion of the supporting bed broken out, and, Fig. 3, a central longitudinal, vertical section through said machine, taken on lines 3—3, looking in the direction of the associated arrow, in Fig. 1.

Similar reference characters designate similar parts throughout the several views.

In Figs. 2 and 3 is represented at 1 a bed, and at 2 a floor line. The bed 1 is supported by any suitable means from the floor, and in each of the two views, wherein said bed 1 and the floor line 2 appear, allowance is not made for the full distance which actually should exist between the two.

Mounted on the bed 1 is a frame 4. The frame 4 has at one end a raised part 5 from which rise two bearings 6. The axes of the bearings 6 are in the longitudinal, vertical, central plane of the frame, and of the machine as a whole. In the top of frame 4, a short distance from the end which is opposite to that where the raised part 5 is located, is an inverted T-slot 7 that extends transversely across said top and opens through opposite edges or sides thereof.

The bearings 6 are bushed, and journaled in said bearings is a shaft 8 on which are mounted between said bearings pulleys 9 and 10. The pulley 9 is loosely mounted on the shaft 8, but the pulley 10 is secured to said shaft by any suitable means, as by a key 11 and two screws 12. A belt (not shown) is provided to drive either of the pulleys 9 and 10, and thus, while in operation, to drive the shaft 8 or permit the same to remain stationary, in the customary manner of tight and loose pulleys.

The shaft 8 extends beyond the inner bearing 6, and mounted on this protruding terminal of said shaft is a hub 13 of a hollow head 14. The head 14 is closed at the outer end and open at the inner end, and the hub 13 is in the center of the closed end. The hub 13 is secured to the shaft 8 by any suitable means, as by a key 15 and two screws 16. Secured inside of the cylindrical wall of the head 14 is an annular liner 17 having on the inside thereof a plurality of integral, circular or annular teeth 18. The spaces between the teeth 18 and said teeth in cross

section, in shape and size, approximate the shape and size of the threads and the spaces therebetween of the worm which this liner, is adapted to act on. The teeth 18 have no lead, however, the liner 17 including the teeth 18 thereof is usually made of leather. The serrated portion of the liner 17 is coated with emery powder or paste, or other abrasive or polishing material, before the work 10 is brought into contact therewith, to facilitate the polishing operation.

Mounted on the top of the frame 4 and extending partly over the T-slot 7 in said top is a plate 19 from which rise a pair of lugs 15 20. This plate forms part of a carrier. The lugs 20 are adjacent to the rear and outer edges of the plate 19, and said lugs having journaled therein a short rock shaft 21, which shaft is or may be parallel with 20 the longitudinal vertical plane of the machine. The plate 19 has therein a slot 22 which is located over the T-slot 7, by means of a bolt 23, and is or may be positioned at right-angles to said T-slot. The bolt 23 has 25 at the lower end a square head 24 that is received in the wider portion of the T-slot 7, and adapted to slide therein, as the shank of said bolt is adapted to slide in the narrower portion of said T-slot. The bolt 23 30 extends above the level of the plate 19, and a nut 25 is threaded onto this upper part of said bolt.

Upon loosening the nut 25, the plate 19 can be moved either to the right or to the left 35 within the limits fixed by the slot 22, can be moved forwardly and rearwardly, the bolt 23 then sliding in the T-slot 7, and can be adjusted on said bolt as an axis. After the plate 19 has been moved and adjusted to 40 whatever extent may be needed, the nut 25 is retightened. The adjustment thus afforded enables the work to be set at such an angle to the axis of the liner 17 as is required by the lead angle and hand of the 45 work, that is to say, of the worm to be polished, as will subsequently more clearly appear.

Mounted on the shaft 21 and extending forwardly therefrom over the top of the 50 plate 19 is an arm 26, from which arm rises a bushed bearing 27. The arm 26 is also a part of the aforesaid carrier. The axis of the bearing 27 is parallel with the axis of the shaft 21. The bearing 27 is provided for 55 a work-holding spindle 28. The spindle 28 is adapted to be reciprocated and rotated in the bearing 27.

A foot treadle 29 has its rear end pivotally attached at 30 to a bracket 31 secured 60 to the floor (2). A cord 32 connects the treadle 29 with the arm 26, the upper end of said cord being attached at 33 to the forward end of said arm, and the lower end of said cord being attached at 34 to said treadle 65 forward of the pivot 30. The cord 32 passes

through vertical openings 40 and 41 made in the top of the frame 4 and in the bed 1, respectively, to accommodate said cord.

The spindle 28 is split and made hollow at the inner terminal, and said terminal is internally screw-threaded as represented at 70 35, in Fig. 3. An expander 36 is provided for the hollow, split terminal of the spindle 28. The passage in the spindle 28, except at the inner terminal, is tapered, as also is 75 the main-body portion of the expander 36, while the inner-terminal portion of said expander is externally screw-threaded, as represented at 37 to engage the screw-threads in 80 said inner-end portion of said passage. The 85 expander 36 is of sufficient length to project from the spindle 28, even when tightened therein, and this protruding part is cylindrical, and provided with a pin 38 which forms a handle to facilitate manipulation of said expander.

The spindle 28 is provided at the outer end with a hand crank 39.

In practice, a worm, as 42, the threads of which correspond in size and shape with the liner teeth 18, is slipped onto the split terminal of the spindle 28, while the expander 90 26 is loose in said spindle, and then said expander is rotated to screw the same tightly into the passage in said spindle. This movement on the part of the expander 36 thrusts the split sections or portions of the spindle outwardly and causes them tightly to engage the sides of the bore in the work 95 42 and thus secure by friction said worm to 100 said spindle. Either before or after the worm 42 is secured to the spindle 28, the nut 25 is loosened and the carrier plate 19 is adjusted to whatever extent may be needed to cause said worm to be presented to or engaged with the liner 17 at the proper angle and hand, and in the otherwise required position to enable the worm to be located on the bottom of said liner. The spindle 28 at 105 this time is disposed outwardly and clear 110 of the head 14. If the carrier plate 19 has not already been adjusted for the type of worm to be polished, said plate is next adjusted to whatever and in whatever directions may be necessary. The spindle 28, 115 with the worm 40 secured thereto, is now raised, the bearing 27 and the arm 26 swinging upwardly on the shaft or pivot 21, and is now moved forwardly in said bearing to carry said worm into the head 14, and then lowered until said worm comes to rest on the liner 17, and said liner is set in motion through the medium of the pulley 10 and the shaft 8. With the worm 40 in the position illustrated in Fig. 3, the same is rotated 120 by hand through the medium of the crank 39 and the spindle 28, and said worm is pressed down into close contact with the liner 17 by means of the pedal 29 acting through the 125 cord 32, the arm 26 with its bearing 27, and

130

the spindle 28, such pressure being varied to whatever extent may be necessary by varying the pressure of the foot on the treadle 28.

- 5 At the end of the polishing operation, the foot is taken from the treadle 28, the arm 26 is lifted far enough to enable the worm threads to clear the liner teeth 18, the spindle 28 is drawn outwardly to remove the 10 worm from the head 14, and said arm is permitted to swing down onto the plate 19 or the top of the frame 4. Finally the expander 36 loosened in the spindle 28 to the extent necessary to release the worm 40, and 15 said worm is withdrawn from said spindle.

The operations just described are performed each time a worm is polished, except that the carrier is adjusted only when the character of the worm calls for such adjustment.

More or less change may be made in the shape, size, construction, and arrangement of some or all of the parts of this machine, without departing from the spirit of my invention or exceeding the scope of what is claimed.

What I claim as my invention, and desire to secure by Letters Patent, is—

1. In a machine, of the class described, a 30 rotary liner, a spindle provided at one terminal with work-holding means, and at the other terminal with means to operate said spindle by hand, and means to support said spindle and enable the same to be moved longitudinally to carry said work-holding means into and out of operative relation with said liner, and to be rotated.

2. In a machine, of the class described, a 40 rotary liner, a spindle provided at one terminal with work-holding means, and at the other terminal with means to operate said spindle by hand, means to support said spindle and enable the same to be moved longitudinally to carry said work-holding means into and out of operative relation with said liner, and to be rotated, and foot-operated means to apply pressure laterally to said spindle and the work carried thereby while in contact with said liner.

3. In a machine, of the class described, a 50 rotary liner, a spindle provided at one terminal with work-holding means, and at the other terminal with means to operate said spindle by hand, means to support said spindle and enable the same to be moved longitudinally to carry said work-holding means into and out of operative relation with said liner, and to be rotated, and means to adjust said spindle at an angle to the axis of 55 said liner.

4. In a machine, of the class described, a 60 rotary liner, a spindle provided at one terminal with work-holding means, and at the other terminal with means to operate said spindle by hand, means to support said spin-

dle and enable the same to be moved longitudinally to carry said work-holding means into and out of operative relation with said liner, and to be rotated, means to adjust said spindle at an angle to the axis of said liner, 70 and foot-operated means to apply pressure laterally to said spindle and the work held thereby while in contact with said liner.

5. In a machine, of the class described, a 75 rotary liner having an interior annular tooth with its sides throughout in parallel planes, and being without a lead, and adapted to interengage worm threads, and a work-holding spindle mounted for longitudinal and rotary movement, whereby said spindle is 80 enabled to cooperate with said liner.

6. The combination, in a machine of the 85 class described, with a hollow rotary head provided on the inside with an interiorly serrated liner, of a bearing, a spindle journaled in said bearing and adapted to be moved lengthwise therein, means to secure a worm to said spindle at one terminal in position to enable the same to be acted on by said liner, when said spindle is moved to bring said worm into contact with said liner and means at the other terminal of said spindle to operate the same by hand.

7. The combination, in a machine of the 90 class described, with a hollow rotary head provided on the inside with a liner which is interiorly serrated, of an adjustable carrier provided with a bearing, a spindle journaled in said bearing and adapted to be moved longitudinally therein, means to secure a 95 worm to said spindle at one terminal in position to enable the same to be acted on by said liner, when said spindle is moved to bring said worm into contact with said liner, and means at the other terminal of said spindle to operate it by hand.

8. The combination, in a machine of the 100 class described, with a hollow rotary head provided on the inside with a liner having interior serrations, of a carrier plate, an arm 105 pivotally connected with said plate, and provided with a bearing, a shaft journaled in said bearing and adapted to be moved lengthwise therein, means to secure a worm to said spindle at one terminal in position to enable the same to be acted on by said liner, when said spindle is moved to bring said worm into contact with said liner, and means at the other terminal of said spindle to operate it by hand.

9. The combination, in a machine of the 110 class described, with a hollow rotary head provided on the inside with a liner having interior serrations, of a carrier plate, an arm pivotally connected with said plate, and provided with a bearing, a spindle journaled in said bearing and movable longitudinally 115 therein, means to secure a worm to said spindle at one terminal in position to enable the same to be acted on by said liner, when 120

said spindle is moved to bring said worm into contact with said liner, means at the other terminal of said spindle to operate the same by hand, a foot treadle, and a connection between said arm and said treadle.

10. The combination, in a machine of the class described, with a frame provided with bearings, a shaft journaled in said bearings, a hollow head secured to said shaft, and provided on the inside with a liner having interior teeth, of a carrier plate on said frame and provided with a bearing, releasable means to secure said plate to said frame, and

15 permit said plate to be adjusted longitudinally and transversely and on said means as an axis, a spindle journaled in said bearing and capable of being rotated and moved longitudinally therein by hand, and means to secure a worm to one terminal of said spindle, whereby the latter can be moved longitudinally in said bearing to carry said worm into contact with said liner, and rotated in contact therewith, and removed from such contact.

20 JULIAN L. PERKINS.
